UNITED STATES PATENT OFFICE

LOUIS UNTERBERGER, OF WILKES-BARRE, PENNSYLVANIA

COMBINATION HUMIDOR AND ADVERTISING DEVICE

Application filed January 12, 1931. Serial No. 508,302.

This invention relates to certain new and useful improvements in humidors and the primary object of this invention is to provide a humidor capable of displaying advertising matter.

The principal object of the present invention is to provide an improved humidor especially adapted to be positioned in display cases for cigars, tobacco and the like.

10 A still further object of the invention is to provide a humidor of the character above mentioned, which is comparatively simple in construction, consists of relatively few parts, will provide a neat and attractive advertising 15 medium, and which will otherwise be well adapted for the purpose designed.

Other objects and advantages of the invention will become apparent during a study of the following description, taken in connection 20 with the accompanying drawings wherein:

Figure 1 is a transverse sectional view taken through a portion of a display case, the humidor being arranged therein.

Figure 2 is a top plan view of a perforated 25 plate forming part of the invention.

Figure 3 is a top plan view of the moistener forming part of the humidor.

Figure 4 is an end view of the plate shown in Figure 2.

30 Figure 5 is a fragmentary detail sectional elevational view showing the manner of suspending the moistener from the perforated plate.

Figure 6 is a fragmentary detail sectional view taken substantially on the line 6—6 of Figure 3.

With reference more in detail to the drawings, it will be seen that the device comprises a relatively flat plate 5 of metal or other suitable material perforated or otherwise provided with holes 6. At each corner thereof plate 5 is provided with a pair of apertures to provide a suspension web 7. At one end thereof plate 5 is provided with an upstanding flange or wall 8 extending transversely of the plate. On the other face of wall 8 may be suitably provided any desired advertising matter. (See Figure 4).

What may be termed a moistener, consists 50 of a relatively flat block like body of clay or

other suitable material designated by the reference character 9. The body 9 is bounded on all four sides thereof by a metal reinforcing frame 10.

The members of frame 10 are channel 55 shaped in cross section for accommodating the edge portion of the clay moistener 9. On the outer faces of the members of the frame 10 may be inscribed, or otherwise formed thereon any suitable advertising matter, as 60 for example the name of the cigar or the like. (See Figure 1).

In actual practice, the plate 5 is adapted to rest on the shelf S of the show case C with the flange or end wall 8 disposed adjacent the 65 front transparent wall of the show case as suggested in Figure 1. The length of plate 5 is preferably greater than the width of the shelf S and suspension elements preferably in the nature of chains 11 are provided at 70 one end with hooks 12 for engaging the suspension web 7. At their lower ends, the chains are suitably anchored to the frame 10 as at 13 whereby the moistener block will be suspended from the plate 5 for disposition 75 below the shelf S.

As also shown in Figure 1, the boxes B of cigars or the like will be placed on the perforated plate 5, and the cigars or tobacco will be maintained in a fresh and wholesome 80 condition.

From the foregoing then, it will be seen that I have devised a humidor that may be readily positioned within a show case for cigars and the like, and which is not only 85 capable of propelling its intended function, but also provides means whereby suitable indicia or advertising matter will be brought to the attention of the observer or prospective purchaser in a novel and attractive manner.

Even though I have herein shown and described the preferred embodiment of the invention, it is to be understood that the same is susceptible to changes, modifications and 95 improvements coming within the scope of the appended claim.

Having thus described my invention, what I claim as new is:

In a device of the class described, a sub- 100

stantially rectangular perforated plate adapted to rest on a support and accommodate a plurality of boxes of cigars or the like, said plate having an upstanding flange at one end thereof and formed at each of its corners with a pair of spaced apertures providing an anchoring web therebetween, said webs being offset below the bottom of the plate for receiving suspension means for a moistening element.

10 In testimony whereof I affix my signature.
LOUIS UNTERBERGER.
